UNITED STATES PATENT OFFICE.

MICHAEL MCANENY, OF DENVER, COLORADO, ASSIGNOR TO GEORGE R. DAVIS, OF CHICAGO, ILLINOIS.

CHANGE-MAKER.

SPECIFICATION forming part of Letters Patent No. 621,124, dated March 14, 1899.

Application filed November 15, 1898. Serial No. 696,537. *No model.*

To all whom it may concern:

Be it known that I, MICHAEL MCANENY, a citizen of the United States of America, residing at Denver, in the county of Arapahoe and State of Colorado, have invented certain new and useful Improvements in Change-Makers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My present invention relates to certain improvements in change-making machines or coin-delivering devices of the class set forth in my previous applications, serially numbered 674,118 and 684,048, respectively. These applications show a casing provided with coin-receptacles, rock-shafts journaled in the casing and provided with depending cranks or fingers engaging slots formed in coin-ejecting slides whose forward extremities are provided with yieldingly-supported tongues or dogs adapted to enter the coin-holders and eject the coins, the bottoms of said receptacles being slotted to receive the tongues, which are depressed below the plane of said bottoms by the gravity of the superimposed coins after the lowermost coin has been ejected. The rock-shafts are further provided with rearwardly-projecting crank-arms and forwardly-extending counter-weights. The crank-arms are connected with vertical push-rods which protrude through the top of the case, their upper extremities being provided with keys or buttons which are provided with characters indicating the amount of change to be delivered by the depression of the button and the downward movement of the push-rods whereby the rock-shafts are actuated. An auxiliary yieldingly-retained rock-shaft is provided with depending fingers engaging slots formed in all the coin-ejecting slides for the purpose of returning the slides to the normal position after each forward thrust. The coin-receptacles are arranged to receive dollars, half-dollars, quarter-dollars, dimes, nickels, and pennies. An auxiliary slide is located adjacent the dollar-slide, normally disconnected therefrom, but

arranged to act simultaneously with each of the other slides. This auxiliary slide is arranged to interlock with the dollar-slide at the will of the operator, whereby an additional dollar may be delivered at any coin-ejecting operation, all as fully set forth and claimed in the said applications.

My present invention involves a number of changes of construction whereby additional functions are performed in some instances, while in other cases the same or similar functions are performed in a different manner or through the medium of additional instrumentalities. These changes are included in the comprehensive term "improvements," and may be briefly noted as follows: The coins are held in a detachable tray, which may be readily removed and another tray substituted whenever for any reason this may be desirable—as, for instance, when it becomes necessary to replenish the exhausted coins. The buttons or keys of the push-rods are provided with numerals indicating the amount of the purchase instead of the amount of change to be delivered. Two additional keys—namely, a two-cent and a five-cent key—are designated by the numerals 2 and 5. These are auxiliary to the other keys and are arranged in such proximity to each other and to the penny-key that they may all be actuated at the same time, if desirable. They are used in making odd amounts of change or amounts not an exact multiple of five. I employ also auxiliary keys, whereby when a purchase is made for a given amount—say five cents—change may be given for different amounts paid. The function of these auxiliary keys and their connections is to depress the coin-ejecting tongues of certain slides so that when thrust forward they shall pass below the coins. For instance, the key which normally gives change for a five-cent purchase is so connected with the slides as to deliver ninety-five cents in change. The auxiliary-key mechanism enables me to depress the fifty-cent tongue, thus reducing the change to forty-five cents if a fifty-cent piece is given, or to depress both the fifty-cent tongue and the twenty-five-cent tongue, thus reducing the change to twenty cents if a twenty-five-cent piece is given, and so on. Another

change consists in employing stops on the coin-ejecting slides, which the fingers of the rock-shafts engage instead of slots, and still another additional feature embraces means 5 for limiting the forward movement of the slides and the downward movement of the push-rods, all as hereinafter set forth more in detail and subsequently pointed out in the claims.

10 In this specification reference is made to the accompanying drawings, in which is illustrated an embodiment of the invention.

In the drawings, Figure 1 is a front end elevation of the mechanism. Fig. 2 is a section taken on the line $x-x$, Fig. 1. Fig. 3 is a section taken on the line $y-y$, Fig. 2, certain of the rock-shafts being omitted. Fig. 4 is a fragmentary rear view in perspective illustrating the operating parts of the machine. Fig. 5 is a top view of the coin-holding tray. Fig. 6 is a perspective view of the same lying on its back to disclose the underneath construction and viewed corner-wise. Fig. 7 is a fragmentary section similar to Fig. 2, but shown on a larger scale. Fig. 8 is an underneath view of the mechanism for depressing the coin-ejecting tongues, whereby one or more of these tongues may be made to pass beneath the coins which they would otherwise eject. The mechanism for causing the auxiliary slide to interlock with the dollar-slide is also shown in this view. Fig. 9 is a section taken on the line $9-9$, Fig. 7. Fig. 10 is a fragmentary longitudinal section taken 35 through one of the rock-shafts and the sleeve mounted thereon for use in connection with the two-cent and five-cent keys. Fig. 11 is a fragmentary side elevation, partly in section, illustrating the mechanism operated by the 40 two-cent and five-cent keys. Fig. 12 is a fragmentary view showing in perspective the auxiliary slide and the adjacent coin-ejecting slide.

Similar reference characters indicating corresponding parts in these views, let the numeral 9 designate the framework of the machine, in which are journaled the rock-shafts 10, having crank-arms 11 and depending fingers 19 for actuating the coin-ejecting slides 14. The crank-arms 11 are connected with rods 12, whose upper extremities are provided with keys 18, upon which are placed numerals to indicate the amount of the purchase. The counterbalance-weights of the rock-shafts are 55 designated by the numeral 21. The spring-supported coin-ejecting tongues 15 are mounted on the forward extremities of the slides 14. The forward ends of these tongues are normally held in position to engage the lower- 60 most coins of the respective receptacles by means of springs 15^a. The two tongues 15, arranged to eject the fifty-cent and twenty-five-cent coins, are adapted to be depressed to occupy a plane below the lowermost coins 65 by means of mechanism which will now be described.

A rock-shaft E is journaled in suitable

brackets F, attached to the under surface of the bottom frame-plate. Upon this shaft is made fast a slotted crank-arm B, through 70 whose slot passes a stem A, made fast to the tongue 15. To the lower extremity of this stem is attached a T-head C, which engages the under surface of the crank-arm, being longer than the width of the slot. The crank-arm B is normally held by a coil-spring E² 75 against the bottom of the base-plate and therefore does not interfere with the normal working position of the tongue 15. To the shaft E is also attached a depending crank-arm K, 80 whose lower extremity is connected with a rod J, which protrudes through the front wall of the case to the left of the coin-discharge mouth 17 of the coin-hopper 16. (See Fig. 1.) To the exposed extremity of this rod is attached a key 31^a, upon which is formed the number 25. By pushing this key the shaft E is given a partial rotation and the slotted crank moved downwardly sufficiently to depress the tongue 15 and cause it to miss the 90 twenty-five-cent coin of the corresponding coin-holder when the slide is actuated.

Fulcrumed on the shaft E is a bell-crank lever D, whose upper arm D¹ is slotted to straddle the stem A, attached to the tongue 95 15, arranged to eject the fifty-cent coins. A T-head C engages the lower surface of this arm. This lever is normally held in such a position as not to interfere with the normal action of the tongue 15 by means of a coil-spring E³, surrounding the shaft, one extremity engaging the bottom plate, while the other extremity is connected with the depending arm D² of said lever. Made fast to the shaft E is a depending arm M, having its lower extremity bent to engage the arm D² of the lever D on the front side. The lower extremity of the arm D² is connected with a push-rod O, whose forward extremity protrudes through an opening formed in the front wall 100 of the frame. The exposed end of this rod is provided with a key 31^b, having the number "50" designated thereon. To depress the fifty-cent-coin-ejecting tongue, it is only necessary to push the key 31^b inwardly, which action 105 will operate the bell-crank lever D and throw its slotted arm downwardly, giving a corresponding movement to the tongue 15, which is thereby made to occupy a plane below the lowermost fifty-cent coin. Through the instrumentalities of the crank-arm M the pushing of the twenty-five-cent key 31^a depresses both coin-ejecting tongues 15 simultaneously. 110

The key 31 adjacent the key 31^b is connected with a crank-arm 29 of a rock-shaft 125 27 by means of a rod 30. This rock-shaft is journaled in brackets 27^a, attached to the bottom of the frame. The shaft 27 is provided with a forwardly-extending crank 28, whose free extremity 28^a is turned upwardly, 130 passing through an opening in the bottom of the case and engaging the auxiliary slide 25, which is normally supported by this crank-arm above the plane of the dollar-slide 14

through the agency of a coil-spring 32, attached to the shaft 27 at one extremity, while its opposite extremity engages the bottom of the frame. The auxiliary slide by its engagement with a finger on the retracting rock-shaft, presently to be described, is moved forwardly at each operation of the device, and when it is necessary to cause the auxiliary slide 25 to interlock with the dollar-slide the key 31 is pressed inwardly and the shaft 27 actuated sufficiently to lower the extremity 28^a of the crank 28, whereby the auxiliary slide is allowed to drop to the plane of the adjacent slide 14. Then whenever the auxiliary slide 15 is thrust forward it engages a shoulder 26 of the slide 14 and carries the latter forward, whereby an additional dollar is ejected from the coin-holding tray.

The detachable coin-holding tray consists of a plate 1, fitted between the sides of the frame and held in place by set-screws 8, which enter registering apertures formed in the connected parts. This plate is provided with segmental receptacles 2, adapted to hold the various denominations of coins in general use, as dollars, fifty-cent pieces, twenty-five-cent pieces, dimes, nickels, and pennies. The coins when placed in these receptacles pass through openings 3, formed in the base of the tray, and rest upon ledges 6, which are provided with central slots 7 to receive the tongues 15 of the slides. In front of the ledges 6 the under surface of the base of the tray is cut away, as shown at 5, to allow the coins to move forward and drop into the discharge chute or hopper 16 when acted on by the ejecting-tongues. These recesses 5 must be of depths respectively equal to the thickness of the various individual coins which are placed in the tray. The two coin-receptacles at the right (see Fig. 1) are designed to hold pennies. The ejecting-tongues 15 are so arranged that two pennies are ejected at a single thrust from the extreme right-hand receptacle, while only one penny is ejected from the other receptacle by a corresponding action. Hence the thickness of the respective recesses 5 must be arranged accordingly. The next two receptacles in order toward the left are intended to hold dimes, the next one nickels, the next quarter-dollar pieces, the next half-dollars, and the extreme left-hand receptacle dollars. The elements of the machine shown in the drawings are so constructed and arranged that only a single coin is ejected at a single thrust of the slide from each receptacle except the penny-receptacle at the extreme right, as heretofore explained. The invention, however, is by no means limited to this construction, as will be readily understood.

The two additional keys employed in my improved machine are designated by the reference characters 18^a and 18^d, and they are respectively provided with the numerals 2 and 5, while the one-cent key is designated by the reference character 18^c. Different reference

characters are employed for these keys for the reason that the numeral of each of these keys indicates the amount to be obtained by pushing the key instead of the amount of the purchase, as shown on each of the other keys, except the dollar-key, which when actuated also gives the amount indicated on the key. These keys when pressed actuate slides which eject two-cent, one-cent, and five-cent coins, respectively. The rod 12 of the two-cent key engages a crank-arm 11, fast on a sleeve 11^a, mounted on one of the rock-shafts 10. This sleeve is also provided with a finger 19, which actuates the coin-ejecting slide 14, whereby two pennies are ejected. The rod 12 of the one-cent key is connected with a crank-arm 11, made fast to a rock-shaft 10 in the usual manner. The rod 12 of the five-cent key 18^d is connected with a crank-arm 11, fast on a sleeve 11^c, mounted on a rock-shaft 10 and provided with a finger which actuates a slide arranged to eject a five-cent coin. Each of the slides 11^a and 11^c is provided with a counterbalance-weight 21 for the purpose of returning the sleeve to its normal position after each sleeve has been actuated for the purpose of ejecting a coin.

The slides 14 are provided with stops 20, which project above the surface of the slides. These stops are located in front of the fingers 19, which normally engage them. Most of the slides 14 are each provided with a number of stops 20, whereby different fingers are arranged to actuate the same slide. In this case when one finger actuates a slide the other finger or fingers arranged to operate the same slide remain inactive, the slide moving under the inactive fingers. The stops 20^a are located to the rear of the fingers 19^a of the rearmost shaft 10^a, which is provided with a hooked crank 24, connected with a spring 23 for returning the slides to their normal position after each forward thrust. The finger 19^c of the shaft 10^c, which actuates the auxiliary slide 25, enters an opening in the slide the same as shown in my previous application.

The downward movement of the push-rods 12 is limited by means of slotted plates 40, attached to the rear end of the case and projecting over two of the slides 14, whose rear stops 20^a project into the slots and engage them as the slides are actuated. Two of the fingers enter these slots and are engaged in the rear by the stops 20^a, which carry the fingers 19^a forward. When these fingers reach the forward extremities of the slots, their movement, as well as that of the slides, the rock-shafts, and the push-rods, is checked.

From the foregoing description the operation of my improved machine will be readily understood. All the keys, except the dollar-key, the nickel-key 18^a, the one-cent key, and the two-cent key, are provided with numerals indicating the amount of the purchase, and when actuated alone produce through the co-operation of the parts with which they are connected an amount of change equal to

the balance left after deducting the amount of the purchase from one dollar, which is assumed to be the amount most often given in payment. If a two-dollar bill is given in payment, the dollar auxiliary key 31 is pressed inwardly, which, in coöperation with the connected parts, interlocks the auxiliary slide 25 with the dollar-slide, thus ejecting an additional dollar no matter which purchase-amount key is actuated, since the auxiliary slide 25 is actuated simultaneously with the movement of every slide operated by a purchase-amount key. If less than one dollar is given in payment—fifty cents, for instance—the fifty-cent auxiliary key 31^b is actuated, which, in conjunction with the connected parts heretofore described, depresses the tongue 15 of the fifty-cent slide, so that it passes under the lowermost coin of the stack, resulting in subtracting fifty cents from the amount of change which otherwise would have been delivered by the movement of any purchase-amount key. Again, if only twenty-five cents is given in payment the twenty-five-cent auxiliary key 31^c is actuated, which, in conjunction with its connections already described, depresses the tongues of the fifty-cent slide and the twenty-five-cent slide, thus subtracting seventy-five cents from the amount of change which otherwise would have been delivered by the normal operation of the purchase-amount key. Whenever the amount of change to be given is a nickel, it can be obtained by pressing the five-cent key 18^d or the ninety-five-cent purchase-amount key, as may be desired. If one dollar is given for a sixty-eight-cent purchase, I press the two-cent key 18^a and the seventy-cent purchase-amount key, obtaining thirty-two cents in change. If the cost of the purchase is sixty-seven cents, I press the one-cent key and the two-cent key simultaneously and then the seventy-cent purchase-amount key, obtaining thirty-three cents in change. If the amount of the purchase is sixty-two cents, I press the one-cent key and the two-cent key by a single act of the hand and then the sixty-five-cent purchase-amount key, obtaining thirty-eight cents in change. These odd prices of articles are much in vogue, especially in the department-stores, and I have equipped my machine to fulfil the resulting change-making requirement. If one dollar is given when the purchase-price is five cents or any exact multiple of five cents, it is only necessary to press one of the purchase-amount keys whose number beginning with five increases by a common difference of five until the maximum number ninety-five is reached. In each case the amount of change delivered will be the difference between the number of the purchase-amount key and one dollar, thus obviating the necessity of any calculation whatever on the part of the user of the machine.

The forward portion of each of the keys exposed at the top of the case is inclined

downwardly to bring the numbers designated thereon into view from a position in front of the machine, the rear part of each key being horizontal to facilitate downward pressure in operating the coin-ejecting devices.

Having thus described my invention, what I claim is—

1. In a machine of the class described, the combination with a number of coin-receptacles, of a plurality of coin-ejecting slides provided with lugs or projections, a plurality of rock-shafts having fingers adapted when moved in one direction to engage lugs or projections of certain of the slides and cause the latter to enter certain of the receptacles, and means independent of said fingers for automatically retracting the slides, substantially as described. 85

2. In a machine of the class described, the combination with a number of coin-receptacles, of a plurality of coin-ejecting slides provided with lugs or projections, a plurality of rock-shafts having fingers adapted when moved in one direction to engage lugs or projections of certain of the slides and cause the latter to enter certain of the receptacles, and a yieldingly-retained rock-shaft having fingers engaging other lugs or projections of all 95 of the slides for retracting the latter, substantially as described.

3. In a machine having coin receptacles and slides provided with yieldingly-supported tongues adapted to enter said receptacles and 100 eject the coins, means for depressing a tongue to cause it to miss the lowermost coin, consisting of a yieldingly-retained rock-arm operatively connected with the tongue, and means for actuating said arm said means being operative from without the casing, substantially as described. 105

4. In a machine having coin receptacles and slides provided with yieldingly-supported tongues adapted to enter said receptacles and 110 eject the coins, of means for depressing a tongue to cause it to miss the lowermost coin of the receptacle, said means comprising a yieldingly-retained rock-shaft, a slotted crank-arm made fast thereon, a stem attached 115 to the tongue and passing through the slot of the crank-arm, its lower extremity having a stop to prevent it from passing through the slot of the arm, and arranged to slide thereon, and suitable means for actuating the rock-shaft. 120

5. In a machine having coin receptacles and slides provided with yieldingly-supported tongues adapted to enter said receptacles and 125 eject the coins, of means for depressing a tongue to cause it to miss the lowermost coin of the receptacle, comprising a yieldingly-retained rock-shaft, a slotted crank-arm fast thereon, a stem attached to the tongue and passing through the slot of the crank-arm, 130 its lower extremity having a stop to prevent it from passing through the slot of the frame and arranged to slide thereon, and suitable means for actuating the rock-shaft, said means

comprising a push-rod having an exposed key, and a crank-arm attached to the rock-shaft but connected with the push-rod.

6. In a machine having coin receptacles and slides provided with spring-supported tongues adapted to enter said receptacles and eject the coins, of means for simultaneously depressing two tongues, to cause them to miss the coins, said means comprising a yieldingly-retained rock-shaft, a slotted crank-arm fast on said shaft, a stem attached to a tongue, passing through the slot of the arm and having a stop engaging the arm, a spring-retained bell-crank lever mounted on said shaft and having one arm slotted, a stem attached to the other tongue, passing through the crank-arm and having a stop engaging the arm underneath, a crank-arm fast on the shaft, a push-rod connected with the crank-arm, and another crank-arm fast on the shaft and engaging one arm of the bell-crank lever, whereby the movement of the shaft actuates the lever, as well as the slotted crank-arm, and draws both tongues downward below the plane 25 of the coins.

7. In a change-maker having a coin-ejecting slide and an auxiliary slide arranged to interlock with the coin-slide, the combination of means for supporting the interlocking part 30 of the auxiliary slide above the plane of the coin-slide, comprising a rock-shaft having a crank-arm whose free extremity engages the auxiliary slide from beneath, a crank-arm attached to the rock-shaft, and an actuating 35 push-rod connected with the crank-arm.

8. In a change-maker, the combination with coin-ejecting slides, suitable means for actuating the slides, and a spring-retained rock-shaft provided with fingers engaging the 40 slides, whereby the movement of any slide actuates the shaft, of stationary stops arranged to engage one or more of the fingers of the

spring-retained shaft for limiting the movement of the slides.

9. In a change-maker, the combination with 45 coin-ejecting slides, rock-shafts having fingers engaging the slides, push-rods for actuating the rock-shafts, and a spring-retained rock-shaft having fingers also engaging the stops on the slides, the stops being located at 50 the rear of the fingers, of stationary stops in the path of the fingers of the last-named shaft for limiting the movement of the push-rods and slides.

10. In a change-maker, the combination 55 with coin-ejecting slides, means for actuating the slides to produce the forward movement, a spring-retained rock-shaft having fingers engaging stops forming a projection above the slides and located in the rear of 60 the fingers, of one or more stationary slotted plates arranged above the slides, and into which the said fingers project, the extremities of the said slots limiting the forward movement of the fingers and the slides. 65

11. In a change-maker, the combination with a frame and coin-ejecting slides, of a coin-holding tray detachably connected with the frame and having coin-receptacles and recesses in front of the receptacles for the escape of the coin the walls of said recesses 70 forming guides for the coin, and coin-supporting ledges at the lower end of the receptacles, said ledges being removable and separated to afford a passage for the ejector-slide, substantially as described. 75

In testimony whereof I affix my signature, in presence of two witnesses, this 9th day of November, 1898.

MICHAEL MCANENY.
